FLUID PUMP OR COMPRESSOR

Application filed October 1, 1924. Serial No. 741,082.

The invention relates to hydraulic gas or vapor pumps or compressors, and more particularly to multi-stage centrifugal gas or vapor pumps in which a moving liquid body 5 is used as the active pumping medium.

In the evacuation or compression of gas or vapor, it has been impracticable with designs heretofore proposed, to produce a multi-stage centrifugal pump using a liquid as the 10 active pumping medium, as the liquid could not be held in the second stage, and the pump would therefore be useless. It has also been impossible to produce a single stage pump of this type constructed as heretofore proposed, 15 which would produce a high vacuum, have a high efficiency when pumping gas or vapor under pressure, which would be easy to assemble and in which the clearances between the impeller and stator could be adjusted 20 closely enough to prevent leakage. It has been the practice to introduce the liquid pumping medium into the suction pipe with a result that the ports in the pump were blocked with liquid, thus reducing the efficiency. In refrigeration apparatus using a 25 chemical such as dichloroethylene, carbon tetrachloride, etc., as the refrigerating medium, it becomes necessary to evacuate leakage air from the condenser during the operation of the system, and the device to be described is especially adapted to evacuate this air with a minimum of loss of the refrigerating medium.

Efficient methods of, and apparatus for, 35 separating, scrubbing or purifying gases or mixtures of gases have not heretofore been produced. Also no effective method has heretofore been devised of cooling the gases passing through the pump, with the result that a 40 large volume of gas or vapor was handled at a higher temperature with a corresponding loss in efficiency.

An object of the invention, therefore, is to produce a practical and efficient multi-stage 45 centrifugal pump for gases or vapors in which a liquid is used as an active pumping medium.

Other objects of the invention are to provide a pump of the class described which will 50 produce a high vacuum or will pump gases or

vapors under pressure with a high efficiency; also to provide a pump of the class described which will be easy to assemble and disassemble and which will provide means for adjusting the clearance between the impeller and 55 stator to take up for wear; also to introduce the liquid pumping medium directly into the impeller without blocking up the gas or vapor port and reducing the efficiency of the pump; also to produce a pump which will evacuate 60 the non-condensable gases from the condenser of a refrigeration apparatus with a minimum loss of the refrigerating chemical; also to provide an effective means for cooling the 65 gases or vapors passing through the pump so as to increase the efficiency; also to provide a method of separating, scrubbing or purifying gases or mixtures of gases or vapors which will be highly effective; and also to improve pumping devices and gas treating 70 methods in other respects, as hereinafter specified and set forth in the claims.

In the accompanying drawings:

Fig. 1 is a side elevation of a centrifugal pump embodying my invention. 75

Fig. 5 is a transverse sectional view through the pump on line 5—5, Fig. 3.

Fig. 6 is a fragmentary sectional view 85 taken on line 6—6, Fig. 3.

Fig. 7 is a transverse sectional view through the pump on line 7—7, Fig. 3.

Fig. 8 is a sectional view through the pump on line 8—8, Fig. 3. 90

Fig. 9 is a fragmentary sectional view on line 9—9, Fig. 6.

In the preferred embodiment of the invention, the pump comprises, briefly stated, a spindle rotatably mounted in a stator casing and carrying rotary impellers. The spindle is preferably but not necessarily positioned with its axis vertical and is connected to the shaft of a driving motor by any suitable means. Two or more impeller wheels are se- 100

cured to the spindle, the wheels being eccentrically arranged within circular impeller chambers in the stator, their eccentricity being oppositely disposed to balance the lateral pressures on the impellers. The pumping liquid is caused to flow through the stator and through the impellers in succession so that the gas or vapor is drawn into one impeller, compressed by the liquid and delivered to the next impeller where it is further compressed by the liquid and discharged from the stator. The impellers are provided with suitable adjusting means so that their axial position on the spindle may be varied to maintain the clearance between the stator and impellers as small as possible thus prevent leakage of gas. The pump shown is also provided with an intercooler through which the gas or vapor and liquid passes from one impeller to the next for cooling and condensing the gas or vapor.

Referring to the accompanying drawings, 10 indicates a motor having a base 11 and a preferably vertical shaft 12. The shaft 12 is secured concentrically to the upper or outer end of a spindle 13 by any suitable means, such as a laterally extending pin 14, said spindle being bored out at its upper end to receive said shaft 12. The pump is conveniently provided with two stages, although more stages may be used, and the moving parts of the first stage consist of an impeller 15 having an upwardly extending concentric sleeve 16 slidably fitted to the upper end of the spindle 13. The impeller 15 has a hub 17 from which extend radial blades 18 having a curvature forwardly in the direction of rotation of the impeller. The sleeve 16 has a reduced annular section 19 which is rotatably mounted in the adjacent end or top 20 of the pump. The axial position of the impeller 15 on the spindle 13 is adjusted by suitable means which are preferably constructed as follows. The upper end of said sleeve is threaded to receive an adjusting nut 21 and a locking nut 22. The upper end of the spindle 13 has an annular section 23 of smaller diameter which is threaded to receive a locking nut 24, the nut 21 being positioned between the nuts 22 and 24. A shoulder 25 is formed on the spindle 13 at the bottom of the reduced portion 23, and an inwardly extending annular flange 26 on the nut 21, seats against said shoulder, being held thereagainst by locking nut 24.

The upper edges of the blades 18 are adapted to be set with as little clearance as possible between them and the inner surface 27 of the pump top so as to prevent gas leakage from the impeller. In order to adjust this clearance in assembly or when it becomes too great because of wear, the sleeve 16 is moved relatively to the spindle 13 by means of the nut 21. The impeller is caused to turn with the shaft, preferably by an internal slot 28

formed in the upper end of the sleeve 16, and a set screw 29 threaded into the spindle 13, and slidably received in the slot 28. Any suitable means, such as holes 30 in the peripheries of the nuts 21 and 24, adapted to receive spanner wrenches, may be employed for rotating said nuts and causing the slight movement of the sleeve 16 relative to the spindle 13 necessary for properly adjusting the clearance between the upper edges of the blades 18 and the surface 27. As the pump is preferably, but not necessarily, designed to be immersed in a liquid, it is desirable to cover the rotating nuts 21, 22 and 24 with an annular guard 31. This guard prevents the liquid from whirling and forming a vortex, and the liquid thus provides a liquid seal around the nuts and prevents leakage of air into the pump. The guard 31 shown is constructed in two halves provided with perforated ears 32 through which bolts 33 pass to connect the halves together. An annular flange 35 is formed on the upper end of the guard 31, said flange being adapted to be bolted to the lower face of the motor base 11 or other fixed support. The guard 31 is also provided with internal annular flanges 36 and 37 respectively rotatably fitting the nut 24 and the sleeve 16 below the nuts.

The pump top 20 is hollow, having an annular space between its upper and lower walls divided by a radial wall 40 into a suction chamber 42 and a discharge chamber 43. The chamber 42 is suitably connected to a suction pipe 45, and the chamber 43 is suitably connected to a discharge pipe 47. An arcuate port 48 is formed in the lower wall of the chamber 42 adjacent the inner wall of the chamber, said port being comparatively narrow adjacent the suction pipe 45, but increasing in width in the direction of rotation in the impeller 15 to which it is designed to deliver gas or vapor from the suction pipe 45. The pump top 20 is also provided with a hole 49, preferably in a tapped lug 50, adapted to receive a liquid pipe 51 leading from any source of liquid, such as a pressure tank or centrifugal pump, not shown, if the pump is operated above atmospheric pressure. If the pump is used for maintaining a vacuum, the pipe 51 may be short or entirely omitted so that the refrigerating liquid in which the pump is immersed is drawn into the impeller as the pumping medium.

A hole 52 extends obliquely from the hole 49 so as to deliver the liquid entering the hole 52 into the impeller 15 through the narrow end of the port 48 without blocking up said port and preventing the free passage of gas or vapor therethrough. Preferably, the pump top 20 has a pair of oppositely disposed arcuate flanges 53 which are adapted to be secured by bolts 54 to an annular flange 55 on a pump body or center 56, and the pump top is also provided with three or more upstanding arms 130

57 which are adapted to be secured to the lower surface of the motor base 11 by means of bolts 58. The lower wall of the discharge chamber 43 is provided near the inner wall 6 of the chamber with an arcuate port 59 which diminishes in width in the direction of rotation of the impeller 15 and is adapted to permit the flow of liquid, vapor and gas from the impeller 15 into the chamber 43 and discharge pipe 47.

10 The pump body 56 has an annular chamber 60 in its upper side, eccentric to the impeller, which is considerably larger in diameter than the impeller 15, the center of said chamber 15 being at a distance from the center of the spindle 13 so that a very small clearance exists between the impeller blades 18 and the wall 61 of said recess 60 at one position while a comparatively large clearance exists between said impeller blades 18 and wall 61 at 20 a position diametrically opposite. Thus, when the impeller 15 is rotated at a high speed and a liquid enters the impeller chamber through the port 48, the liquid is caused to 25 rotate by the impeller blades and is thrown outwardly against the wall 61 so as to form an arcuate space between the hub 17 and the surface of the liquid. Thus vapor or gas is drawn into the impeller chamber through the 30 port 48 between the surface of the liquid and the hub 17, and as the liquid again approaches the hub adjacent the port 59, due to the eccentricity of the chamber, the gas and some of the liquid is forced out of the latter port and 35 out through the discharge pipe 47. A shroud 62 is preferably formed on the bottom of the impeller 15 integral with the blades 18 so as to strengthen the same and prevent any gas leakage from the impeller blade as the impeller rotates. The floor 63 of the recess 60 40 has a counterbore 64 substantially the same depth and diameter as the shroud 62, in which said shroud rotates freely.

45 The discharge pipe 47 is connected to an intercooler 65, preferably, but not necessarily in the form of a coil, and said intercooler leads into the second stage suction pipe 66 which is connected in any suitable way with the second stage suction chamber 70 in the 50 pump body 56. The pump and intercooler are preferably submerged in a cooling liquid or refrigerating medium contained in a tank 68 having a cover 68^a, and the motor base 11 is arranged so as to close an opening 69 in said cover through which the pump can be inserted into and removed from the tank 68. Thus, the gas or vapor which has been compressed and heated, due to the increase in pressure in the first stage of the pump, passes 60 through the intercooler 65 which is submerged in the cooling liquid, said gas being mixed with the cold liquid pumping medium from the first stage, so that it is efficiently cooled and reduced to a smaller volume. The cooling 65 is accomplished externally and indirectly

by the cooling liquid in the tank and the gas is cooled directly by the cool liquid pumping medium which flows through the intercooler 65 in contact with the gas so that a very efficient cooling is accomplished. When the 70 pump is used for the evacuation of air or other non-condensable gases from the condenser of a refrigeration system in which a volatile refrigerant such as dichloroethylene, carbon tetrachloride, etc. is employed, it is 75 very convenient to pass some of the refrigerating liquid through the pump as the pumping medium. In this case the liquid refrigerant is supplied to the tank 68 and is utilized as pumping medium, and aids in cooling and 80 condensing out any of the volatile chemicals contained in the gases as the pumping liquid passes through the first stage, intercooler and second stage, so that the loss of the refrigerant is reduced to a minimum.

85 The pump body 56 is hollow and divided by a bottom 71 and a partition 73 into the suction chamber 70, and discharge chamber 72. An arcuate, tapering suction port 75 is formed in the bottom 71 of the body, increasing in width in the direction of rotation of the second stage impeller 76. The impeller 76 has a hub 77 fitted to the spindle 13 and radially disposed blades 78 are formed on said hub, said blades curving forwardly in 90 the direction of rotation of said impeller 76. An upper shroud 79 and lower shroud 80 are preferably formed on the impeller 76 integral with the blades 78, serving to strengthen the 95 blades and prevent the leakage of gas from the impeller. A port 81 is formed in the shroud 79 between each pair of blades 78 adjacent the hub 77, said ports 81 registering with the suction port 75 and a discharge port 82 in the bottom 71 of the chamber 72. The 100 port 82 is arcuate in form and also tapers in the direction of rotation of the impeller 72. A counter-bore 83 is formed in the lower surface of the bottom 71, in which the shroud 79 is rotatably fitted with a very small clearance 105 therebetween so as to prevent the leakage of gas from the impeller 76.

110 As shown, the bottom 71 of the pump body 56 is formed with a flange 84 (see Figs. 7 and 8), and is secured by bolts 85 to an annular flange 86 formed on a pump bottom 87. A 115 plurality of lugs 88 is also formed on the flange 84, said lugs being closely received inside of upstanding ears 89 formed on similarly spaced lugs integral with the flange 86 120 so as to properly position the pump bottom 87 relatively to the pump body 56 when assembling. An annular eccentric recess 90 is formed in the top of the pump bottom 87, said recess being considerably larger in diameter than the impeller 76 and having its center at a distance from the center of the spindle 13. The internal annular wall 91 125 of the recess 90 is thus spaced with a very small clearance at one position of the impeller 130

76 and with a much larger clearance at a position diametrically opposite to the eccentric space 61 of the first stage, so as to balance the pressure of the pumping liquid in the two stages. The liquid pumping medium drawn into the impeller 76 through the port 75, follows the wall 91 as the impeller 76 rotates at a high speed, so that a space for the gas is left between the hub 77 and the surface of the liquid. The gas therefore enters this space in the impeller 76 through the port 75, and as the liquid pumping medium is again forced toward the hub 77 adjacent the port 82, the gas and some of the liquid pumping medium is forced out of the impeller through said port 82 into discharge chamber 72 and out of a discharge pipe 92 secured by any suitable means to said discharge chamber 72. The pipe 92 leads upwardly through the motor base 11 to any suitable trap or separating device, not shown, which separates the liquid pumping medium from the gas and returns the former to the refrigeration system, discharging the gas into the atmosphere. The suction line 45 also leads up through the motor base 11 so that the motor and pump may be easily removed as a unit from the tank cover 68 for inspection or repairs.

30 The shroud 80 of the impeller 76 is rotatably received in a counter-bore 94 in the floor 95 of the recess 90, said counter-bore having substantially the same depth and diameter as the shroud 80. In order to accurately adjust the clearance between the shroud 79 and the counter-bore 83 to take up for wear, etc., the impeller hub 77 has a downwardly extending sleeve 96 fitted around the spindle 13, and said sleeve is threaded to receive an adjusting nut 97 and a lock nut 98 similar to those in the first stage. The spindle has a threaded lower end 99 of reduced diameter forming a shoulder 100. An inwardly extending annular flange 101 on the nut 97 is adapted to be forced against the shoulder 100 by a locking nut 102 on the threaded section 99. In order to cause the impeller 76 to rotate with the spindle 13, a set screw 104 is shown screwed to the sleeve 96, the inner end of said screw being received by a slot 105 in the spindle 13, this arrangement also permitting axial movement of the sleeve 96 relatively to the spindle 13 when the nuts 97, 98 and 102 are adjusted.

55 A cylindrical casing 106 having a closed bottom 107 is formed on the pump bottom 87 and surrounds the adjusting nuts and lower end of the spindle so as to make a gas tight casing for the pump. The pump top, 60 body and bottom are consecutively secured one to the other so as to permit easy assembly and the three sections form a stator which is attached to the motor to form a conveniently handled unit.

65 The pump described is highly efficient in

separating, scrubbing or purifying gases or vapors. Thus a liquid pumping medium may be selected to remove a gas, liquid or vapor from other gases by dissolving out or chemically combining with ingredients of the gas. 70 The gas or vapor remaining is compressed by the pump while the purification or scrubbing action takes place. The gas or vapor is thoroughly mixed with the pumping liquid by the impeller blades it passes through the 75 intake ports of the first and second stage so that the purifying and scrubbing action is thorough.

In the operation, the gas or vapor to be compressed is drawn into the suction chamber 42 of the pump through suction pipe 45 and is then drawn into the impeller 15 through port 48. The liquid pumping medium is introduced into the impeller 15 through hole 52 and through the narrow end of the 80 suction port 48. The liquid follows the eccentric outer wall 61 of the recess 60 forming a space for the vapors between the surface of said liquid and the hub 17 of the impeller 15. As the impeller 15 continues to 85 rotate, the gas and some of the liquid pumping medium are forced out of the discharge port 59 as the surface of the liquid again approaches the hub 17. When passing out of the port 59, the gas and some pumping liquid 90 pass into the discharge chamber 43, out of the discharge pipe 47, through the intercooler 65, pipe 66 and into the suction chamber 70 of the second stage of the pump. The gas and the liquid pumping medium are then 95 drawn into the second stage impeller 76 through the port 75. The liquid pumping medium then follows the outer wall 91 of the recess 90 so as to form a space for the gas between the hub 77 of the impeller 76 and the surface of the liquid. Continued rotation of the impeller 76 then forces the liquid back in contact with the hub 77 so that the gas and some of the liquid pump medium flows 100 out of the port 82 into discharge chamber 72 and out through discharge pipe 92.

In order to adjust the clearance between the upper surface of the impeller blades 18 and the lower surface 27 of the pump top 20, the adjusting nut 21 is rotated slightly after loosening the lock nuts 22 and 24. Then the lock nuts 22 and 24 are again tightened, the annular flange 26 on the nut 21 contacts with the shoulder 25 on the spindle 13 so as to properly adjust said clearance, while the lock nut 22 prevents any further rotation of the nut 21.

The connection described for causing the impeller 76 to rotate with the spindle 13 also permits a slight axial movement therebetween. In order to adjust the clearance between the impeller 76 and the counter-bore 83, the lock nuts 98 and 102 are loosened. The adjusting nut 97 can then be turned slightly to adjust said clearance and then the 130

lock nuts 93 and 102 are again tightened to cause the adjusting nut flange 101 to seat securely against the spindle shoulder 100.

In the following claims, except where a different meaning is obvious, the word "gas" has been used to mean a simple or mixed gas, such as air, or a mixture of gas or gases and a vapor.

Having thus described my invention, I claim as new and desire to secure by Letters Patent:

1. In a centrifugal pump in which a liquid acts as a pumping medium for a gas, a plurality of rotary impellers arranged in axial alinement and connected to rotate together, each adapted to cause the rotation of the pumping liquid, means for causing the pumping liquid to pass from one to another of said impellers and be acted upon by said impellers in succession so as to cause a gas to be received at a low pressure by one impeller and delivered at a higher pressure by another impeller, and means for adjusting the axial position of an impeller to regulate the clearance between the impeller and an opposed part of the pump.

2. In a centrifugal pump in which a liquid acts as a pumping medium for a gas, a plurality of rotary impellers arranged in axial alinement and connected to rotate together, each adapted to cause the rotation of the pumping liquid, means for causing the pumping liquid to pass from one to another of said impellers and be acted upon by said impellers in succession so as to cause a gas to be received at a low pressure by one impeller and delivered at a higher pressure by another impeller, and means for independently adjusting the position of said impellers so that the clearance between the same and opposing parts of the pump is regulated to prevent leakage of gas from the impellers.

3. In a centrifugal pump in which a liquid acts as a pumping medium for a gas, a plurality of rotary impellers secured to a driven shaft, each adapted to cause the rotation of the pumping liquid, means for causing the pumping liquid to pass successively through said impellers so as to cause a gas to be received at low pressure by one impeller and be delivered at a higher pressure by another impeller, and means for adjusting the axial position of an impeller relative to said shaft to regulate the clearance between the impeller and an opposed part of the pump.

4. In a centrifugal pump in which a liquid acts as a pumping medium for a gas, a stator, a driven rotary shaft, an impeller secured to said shaft inside said stator adapted to cause the rotation of the pumping liquid, means for passing the pumping liquid through said impeller so as to cause a gas at a low pressure to be received by the impeller and discharged from the stator at a higher pressure, and means for adjusting the position of said im-

peller relative to said stator so that the clearance therebetween is regulated to prevent leakage of gas from the impeller.

5. In a centrifugal pump in which a liquid acts as a pumping medium for a gas, a stator, a driven rotary shaft, a plurality of impellers secured to said shaft inside said stator, each adapted to cause the rotation of the pumping liquid, means for successively passing the pumping liquid through said impellers so as to cause a gas at a low pressure to be received by one impeller and discharged from another impeller at a higher pressure, and means for independently adjusting the position of said impellers relative to said stator so that the clearance therebetween is regulated to prevent leakage of gas from the impellers.

6. In a vacuum gas pump having a gas inlet and a gas outlet, a plurality of driven impellers, means for successively passing a pumping liquid and the gas from one to another of said impellers so that the gas is received at a low pressure by one impeller and delivered by another impeller at a higher pressure, and means for cooling the gas and liquid as they pass from one impeller to another impeller.

7. In a vacuum gas pump having a gas inlet and a gas outlet, a plurality of driven impellers, means for successively passing a cold pumping liquid from one to another of said impellers so that the gas is received at a low pressure by one impeller and delivered by another impeller at a higher pressure, and an intercooler between two of said impellers adapted to conduct the gas and cold liquid therebetween and cool the gas and liquid.

8. In a vacuum gas pump having a gas inlet and a gas outlet, a plurality of driven impellers, means for successively passing a cold pumping liquid from one to another of said impellers so that a gas is received at a low pressure by one impeller and delivered by another impeller at a higher pressure, an intercooler arranged to conduct the gas and liquid from one impeller to another impeller and cool them during transfer, and means for cooling the intercooler externally so as to aid in cooling the gas and liquid.

9. In a pumping device in which a liquid acts as a pumping medium for a gas, a plurality of rotary impellers each adapted to cause the rotation of the pumping liquid, means for causing the pumping liquid to pass successively from one to another of said impellers and be acted upon by said impellers in succession so as to cause a gas to be received at low pressure by one impeller and be delivered at a higher pressure by another impeller, said pumping device having separate inlet ports for the gas and for the pumping medium.

10. In a centrifugal pump, a driven shaft, a plurality of impellers secured to said shaft, a stator enclosing said impellers, a port in

- 5 said stator adjacent one of said impellers, separate means for the admission of a pumping liquid to said impeller so as to draw a gas at low pressure through said port to said impeller, said impeller being adapted to increase the pressure of and deliver said gas to another impeller, and means for conducting said gas from the second impeller and said stator at a still higher pressure.
- 10 11. In a centrifugal pump, a stator, a plurality of rotary impellers arranged in said stator to provide an eccentric space between the stator and each impeller, said spaces for two impellers being oppositely and diamet-
- 15 rically disposed to each other, and means for passing a pumping liquid through said stator spaces from one to another of said impellers so that said liquid accomplishes a pumping action on passing therethrough thus caus-
- 20 ing a gas at low pressure to be received by one impeller and delivered by another impeller at a higher pressure.
12. In a centrifugal pump, a fixed support, a plurality of stator sections adapted to be
- 25 successively secured to said fixed support, a driven shaft rotatably mounted in said stator sections, a plurality of impellers secured to said shaft in said stator sections, and means for passing a pumping liquid
- 30 through said stator sections from one to another of said impellers so that a gas at low pressure is received by one impeller and delivered from another impeller at a higher pressure.
- 35 13. In a centrifugal pump, and in combination, a container for a liquid, a stator submerged in the liquid in the container, gas inlet and discharge connections, a plurality of rotary impellers arranged in said stator,
- 40 and means for passing said liquid as a pumping medium through said stator from one to another of said impellers so that a gas at low pressure is received by one impeller and delivered from another impeller at a higher pressure.
- 45 14. In a centrifugal pump, a stator, a driven shaft rotatably mounted in said stator, a plurality of impellers concentrically arranged on said shaft, adjusting nuts associated with said impellers and said shaft and adapted to adjust the position of said impellers axially of said shaft to regulate the distance between said impellers and said stator, and means for passing a liquid pumping medium through said stator and impellers so that a gas at low pressure is received by one impeller and delivered from another impeller at a higher pressure.
- 50 15. In a pumping device, a pump top, a pump bottom, a pump body secured between said pump top and bottom so as to form a sectional stator, a shaft rotatably mounted in said stator, a low pressure and a high pressure impeller secured to said shaft in
- 55 said stator, means for causing a pumping liquid

uid to be acted upon by said impellers in succession, and means for introducing a low pressure gas to be compressed into the stator and low pressure impeller and delivering said gas at a higher pressure from the second impeller and stator.

70 16. In a pumping device, a pump top, a pump bottom, a pump body secured between said pump top and bottom so as to form a sectional stator, a shaft rotatably mounted in said stator, a low pressure and a high pressure impeller secured to said shaft in said stator, means for causing a pumping liquid to be acted upon by said impellers in succession, means for introducing a low pressure gas to be compressed into the stator and low pressure impeller and delivering said gas at a higher pressure from the second impeller and stator, and means for independently adjusting the position of the impellers relative to said stator.

75 17. In a vacuum pumping device, a pump top, a pump bottom, a pump body secured between said pump top and bottom so as to form a sectional stator, a shaft rotatably mounted in said stator, a low pressure and a high pressure impeller secured to said shaft in said stator, means for causing a pumping liquid to be acted upon by said impellers in succession, means for introducing a low pressure gas to be compressed into the stator and low pressure impeller and delivering said gas at a higher pressure from the second impeller and stator, and means for independent-

80 ly adjusting the position of the impellers relative to said stator.

85 18. In a vacuum pump for gases utilizing the liquid of the gas as the pumping medium,

90 a plurality of rotary impellers each causing a rotation of the pumping liquid, means for conducting the pumping liquid from one impeller to another in succession, means for admitting the gas to the inlet of a low stage impeller and removing it from the outlet of a higher stage impeller, whereby said liquid and gas will pass together through and between said impellers, and means for cooling said liquid and gas while passing between said impellers.

95 19. In a vacuum pump for gases utilizing a working liquid as the pumping medium, a plurality of rotary impellers, each causing a rotation of the pumping liquid, a gas inlet leading to and an outlet leading from each impeller, a connection from the outlet of one impeller to the inlet of another to cause the gas to pass in succession through said impellers, and means for cooling said connection whereby the gas will be handled in a cold condition in both impellers.

100 20. In a vacuum pump for gases utilizing a working liquid as the pumping medium, a plurality of rotary impellers, each causing a rotation of the pumping liquid, a gas inlet leading to and an outlet leading from each

impeller, a separate liquid inlet leading to one impeller at a point adjacent the gas inlet, a connection from the outlet of said one impeller to the inlet of another to cause the gas and some of the pumping liquid to pass in succession through said impellers, and means for cooling said connection whereby the gas and liquid will be handled in a cold condition in both impellers.

5 21. The process of creating a vacuum for a vapor with a rotating body of the liquid of the vapor as the working fluid, which comprises pumping and compressing the vapor through a plurality of stages with the liquid 10 of the vapor as the pumping liquid, and cooling the vapor and liquid between stages to avoid the breaking of the vacuum by a high vapor pressure of the pumping liquid.

15 22. The process of pumping a gas to create a vacuum which comprises compressing and transferring said gas with a rotating body of the liquid of said gas as the pumping medium, through a plurality of stages, and cooling the gas between stages of compression to decrease its volume to provide a low 20 vapor pressure of the pumping liquid, and the creation of a relatively high vacuum at the intake side of the second stage.

25 23. The process of compressing and condensing a vapor, which comprises compressing and pumping said vapor with a rotating body of the liquid of the vapor as the pumping medium, through a plurality of successive stages, and cooling the gas and liquid being pumped to maintain a low vapor 30 pressure of the pumping liquid, whereby breaking of the vacuum in the second stage by the vaporization of the liquid will be avoided.
